UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

AUTOMOBILE-CLOCK.

1,292,043.

Specification of Letters Patent.

Patented Jan. 21, 1919.

Application filed October 17, 1917. Serial No. 197,149.

To all whom it may concern:

Be it known that I, WILSON E. PORTER, a citizen of the United States, residing at New Haven, in the county of New Haven 5 and State of Connecticut, have invented a new and useful Improvement in Automobile-Clocks; and I do hereby declare the following, when taken in connection with the accompanying drawings and the characters of reference marked thereon, to be a full, clear, and exact description of the same, and which said drawings constitute part of this application, and represent, in—

Fig. 1 a view in front elevation of a rear-wind and rear-set automobile clock and housing therefor, constructed in accordance with my invention and shown as applied to the cowl-board of an automobile.

Fig. 2 a view thereof in vertical section on the line 2—2 of Fig. 1, with the clock proper mainly shown in side elevation.

Fig. 3 an enlarged broken detail sectional view showing the construction of the clock and housing for locking the former 25 in place in the latter, with ample clearance for the clock-case within the housing.

Fig. 4 a detached plan view of the housing with the clock in its locked position therein.

Fig. 5 a view in elevation of the housing, showing the large coiled ejecting-spring in the bottom thereof.

Fig. 6 a view in rear elevation of the clock proper.

My invention relates to an improvement in rear-wind and rear-set automobile clocks and housings therefor, the object being to produce a clock and housing of simple, compact, durable and convenient construction, 35 designed with particular reference to locating the face of the clock bezel as nearly flush as possible with the surface of the cowl-board.

With these ends in view, my invention 45 consists in a rear-wind and rear-set automobile clock and housing therefor, having certain details of construction as will be hereinafter described and pointed out in the claims.

In carrying out my invention, as herein shown, I employ a rear-wind and rear-set 50 clock of any approved construction so far as its movement is concerned. As herein shown, this clock has a laterally projecting flattened bezel 3 the outer edge of which

is knurled as at 4 for being gripped by the tips of the fingers for rotating the clock as required to lock it within, and unlock it from, a cup-shaped container or housing 5 closed at its rear end and provided at its forward end with a fastening-flange 6 60 formed with countersunk screw-holes 7 by means of which the housing is secured by screws 8 to the cowl-board 9 which is formed with a circular opening 10 into which the housing is set. The rear face of the outer edge of the bezel 3 bears directly upon the outer face of the fastening-flange 6 from which the bezel 3 projects only to the extent of its own thickness. The said 70 bezel 3 is formed upon its inner face with an integral, annular centering-band or supporting flange 11 adapted in internal diameter to fit snugly within the open outer end of the cup-shaped housing 5 in which it centers the cylindrical clock-case 12, the open forward edge of which is fitted snugly within the said band 11 and secured thereto by solder, or otherwise, as shown in Fig. 3. Since the external diameter of the clock-case 12 is smaller than the internal diameter of the housing 5, an annular clearance space 13 is formed between them when the 75 clock is in position in the housing. The use of the centering-band 11 makes it unnecessary to fit the clock-case, as a whole, into the housing and makes it easy to introduce the clock into the housing and to remove it therefrom.

For locking the clock in the housing, I 80 employ, as shown, two radially arranged locking-pins 16 mounted at opposite points in the centering-band 11, but also extending inward into the outer edge of the cylindrical clock-case 12. These pins are adapted 85 in length and in position to engage directly with the rear face of the fastening-flange 6. For this purpose the inner edge of the said flange is formed at opposite points with radial entrance-notches 17, the inner 90 ends of which intersect clearance-slots 18 formed in the extreme forward edge of the housing 5 and concentric therewith.

For preventing the clock from rattling within the housing and also for partially 105 ejecting it preparatory to being grasped for entire removal therefrom for winding and setting, I employ an ejecting-spring 19 located at the bottom of the housing and sufficiently large in diameter to clear the 110

winding-key 20 and the setting-button 21, both of which project from the back of the clock, which has already been characterized as a rear-wind and rear-set clock.

- 5 As shown, a portion of the rear coil of the spring 19 is made to substantially conform in diameter to the internal diameter of the housing 5 so as to be frictionally retained in place therein, while the forward coil of the 10 spring is sufficiently contracted in diameter not to engage the side walls of the housing so as to be free to exert its full force upon the back of the clock-case 12.

For removing the clock for the purpose of 15 winding and setting it, it is rotated clockwise for the length of the slots 18 to bring its locking-pins 16 into registration with the entrance-notches 17 when the ejection-spring 19 immediately acts to eject the clock sufficiently far from the housing 5 to enable it 20 to be very readily grasped and withdrawn entirely therefrom for being wound and set, after which it is re-introduced into the housing with its pins 16 registered with the 25 entrance-notches 17. The clock is then pushed inward against the tension of the spring 19 until the rear face of its bezel 3 has been brought to a bearing upon the outer 30 face of the flange 6 after which the clock is rotated counter clockwise through its bezel for the engagement of its locking-pins 16 with the rear face of the flange 6, the pins at this time entering the clearance-slots 18. The inner edge of the bezel overhangs the 35 crystal 22 which rests upon the usual mat 23, which in turn rests upon the clock-dial 24. Inasmuch as the clock is not closely fitted into the housing throughout its length, but centered and supported therein only at its 40 outer end by the lateral projection formed by the band 11, the clock is readily removed from, and introduced into the housing. In this connection it may be noted that there is so little friction between the band 11 and the 45 outer end of the housing, that the spring has little friction to overcome in ejecting the clock sufficiently to permit it to be readily grasped by the fingers for being entirely withdrawn from the housing.

50 I claim:—

1. The combination with a housing adapted to be mounted in an automobile, of a rear-wind and rear-set clock having a cylindrical clock-case and an independently formed laterally projecting bezel formed with an in-

wardly extending annular centering-band adapted in external diameter to fit snugly within the forward end of the said housing and in internal diameter to fit over the forward end of the clock-case to which it is secured, and means for removably securing the said clock within the said housing from which it is removed *in toto* for winding and setting.

2. The combination with a housing adapted to be mounted in an automobile and having at its forward end a laterally projecting fastening-flange, of a clock the cylindrical case of which is adapted in diameter to clear the inside of the said housing and which is provided in its forward end with an independently formed laterally projecting bezel which overlaps the said fastening-flange and which is formed with an inwardly projecting annular centering-band fitting within the forward end of the said housing and over the forward end of the clock-case to which the band is secured, and means mounted in the said band for removably securing the clock within the housing from which it is removed *in toto* for winding and setting.

3. The combination with a housing adapted to be mounted in an automobile and formed at its outer end with a fastening-flange, of a rear-wind and rear-set clock having at its rear end rearwardly projecting winding and setting means, and provided at its forward end with a laterally projecting bezel which overlaps the said fastening-flange and which is formed with an inwardly projecting annular centering-band fitting within the forward end of the housing and over the forward end of the clock-case to which it is secured, an ejecting spring interposed between the rear end of the clock and the bottom of the housing and adapted to clear the said winding and setting means at the back of the clock, and means for removing the clock within the housing from which it is removed *in toto* for winding and setting.

In testimony whereof I have signed this specification in the presence of two subscribing witnesses.

WILSON E. PORTER.
